UNITED STATES PATENT OFFICE.

JULIUS WENDLER, OF BERLIN, GERMANY.

REVOLVING DOOR.

No. 921,322.

Specification of Letters Patent.

Patented May 11, 1909.

Application filed December 18, 1906. Serial No. 348,477.

To all whom it may concern:

Be it known that I, JULIUS WENDLER, architect, a subject of the King of Prussia, residing at No. 117/118 Leipzigerstrasse, Berlin, German Empire, have invented new and useful Improvements in Revolving Doors, of which the following is a specification.

My invention has reference to revolving doors, that is to say, to doors turning in one direction only; and relates to means for actuating the same with the aid of a motor.

The essential feature of the invention is the provision of a spring, which is normally under tension, but on slight pressure being applied to one of the door-wings, unwinds and thereby aids in the rotation of the door; and at a given time effects closing of the circuit of an electric motor, which again winds up the spring, independently of the axis of the door, and is then automatically cut out.

One form of construction of the invention is illustrated in the accompanying drawings, in which—

Figure 1 is a side elevation and part section, and Fig. 2 a plan.

On the shaft *a*, which represents the axis on which the door (itself not shown) turns—
but in the direction of the arrow only—, there is loosely mounted the barrel *b*, and below the latter there is likewise loosely mounted the worm wheel *c*. The barrel *b* contains the coiled spring *f*, one end of which is secured to the wall of the barrel *b* and the other to the boss *c* of the worm wheel *c*. The tension of the spring is such that it can only move the door wings, connected with the shaft *a*, when slight pressure is exerted against one of the wings. The worm wheel is connected with an electric motor *i* by means of a worm *g* and two spur wheels *h* *i*. Above the barrel *b* there is keyed on the shaft *a* a ratchet wheel *K*, with which there engages a spring-actuated pawl *l*, pivoted to the barrel. Supposing the door is set in motion: the worm wheel *c* and worm *g* still remaining stationary, the spring *f* will exert a rotary action on the shaft *a* and thus cause or rather, aid, rotation of the door. When the spring *f* has unwound to a certain extent, it will be wound up again by the motor. This is done in the following manner. *m* is a threaded spindle which screws up and down in the nut *n* of the fixed arm *p* and is connected with a lever

o. This spindle is furnished with a spider wheel *q*, whose spokes engage with the lugs or wings *q* of the wheel *c*. A second spider wheel *r* is mounted to turn in a fixed arm *t*. This wheel *r* has no internal thread, but allows the spindle *m* to pass freely through it. It is furnished with a pin *u*, which engages with a stop-collar *v*, rigidly secured to the spindle *m*, so that on rotation of the wheel *r*, owing to the coöperation of the pin *u* with the stop of the collar *v*, rotation of the spindle *m* is effected. The spokes *s* of the wheel *r* engage with the corresponding lugs or wings *s* of the barrel *b*. As seen in Fig. 1, the lever *o* is of double cranked shape carrying the contacts *x* *y*. The inner end of this lever is turned down by means of the rotation of the spindle *m* for starting the motor, bringing the contact *x* up into contact with the fixed contact *x*, and when the said spindle is screwed in the opposite direction by the motor, the contact *y* comes in contact with the fixed contact *y* and stops the motor.

In this form I have shown two axles and a plurality of wings or doors connected for simultaneous movement.

x and *y* are contact plates in the motor circuit for coöperation with contacts *x* and *y* carried by the free end of the lever *o*.

When the door is turned, the motor, worm and worm wheel at first remain at rest, while the barrel rotates, so that the spring is unwound, exerting an action on the door. The wings *s* will now engage with the spokes of the wheel *r*, and the pin *u* with the stop of the collar *v*, whereby the spindle *m* is set in rotation. The spindle thus screws itself down in the nut *n* and thus cuts in the motor by bringing plate *x* on lever *o* against the fixed contact *x*. When the door ceases to be turned, it will, with the barrel, remain stationary, while the motor continues to work at first, and turning the worm wheel *c* by means of the worm *g*, again winds up the spring *f*. At the same time the wings *q* of the worm wheel *c* will rotate the nut *n*, whereby the spindle *m* works up again and separates the plates *x* and *y* and thus cuts out the motor.

Having thus described my invention, what I claim as new and desire to secure by Letters Patent is:—

1. In revolving doors, in combination, a door axis; a ratchet wheel rigidly mounted thereon; a barrel having a pawl which engages with the ratchet wheel, and a second

wheel, both loosely mounted on the axis; a spring coiled within the barrel with its one end attached to the latter and the other to the second said wheel; an electric motor driving the latter; a screw spindle; and means on said spindle operated by the rotating barrel for working the spindle in one direction, in order to make the motor-circuit; and means on said spindle operated by the rotating 10 second said wheel for working the spindle in the opposite direction, in order to break the motor-circuit; substantially as described.

2. In revolving doors, in combination, a door axis; a ratchet wheel rigidly mounted thereon; a barrel provided with peripheral lugs, having a pawl which engages with the ratchet wheel, and a gear wheel provided with peripheral lugs, both loosely mounted on the axis; a spring coiled within the barrel 15 with its one end attached to the latter and

the other to the gear wheel; an electric motor driving the gear wheel; a vertical screw spindle; a framing having a nut in which the spindle works; a spider wheel on the spindle, engaging with the gear wheel 25 lugs; a second spider, provided with an arm, carried by the framing and through which the spindle freely passes and with which the barrel lugs engage; a stop on the spindle engaging with the said arm; and a 30 motor-circuit making and breaking lever actuated by the spindle; all operating substantially as described.

In witness whereof I have hereunto signed my name this 3rd day of December 1906, in the presence of two subscribing witnesses.

JULIUS WENDLER.
